BRANDING TOOL FOR BARBECUED STEAKS

Norman S. Andrews, Dundee, Ill.

Application April 13, 1959, Serial No. 55,469

Term of patent 3½ years

(Cl. D81—10)

Fig. 2.

Fig. 3.

Fig. 4.

Fig. 1 is a perspective view of a branding tool for barbecued steaks, showing my new design;

Fig. 2 is a top plan view thereof;

Fig. 3 is an elevational view of one side thereof; and
Fig. 4 is a bottom plan view thereof.

The dominant features of my new design reside in the portions shown in full lines.

I claim:

The ornamental design for a branding tool for barbecued steaks, substantially as shown and described.
